UNITED STATES PATENT OFFICE.

CHARLES T. HELLER, OF ST. PAUL, MINNESOTA.

SPOUT.

Application filed August 16, 1926. Serial No. 129,428.

My invention relates to spouts for draining containers having a discharge neck, and has for an object thereof to provide a spout adapted to be applied to a container neck and 5 formed with a nozzle for conducting the contents of the container therefrom in a uniform stream, said nozzle being provided with a vent for admitting air to the container as the contents of the container is removed so as 10 to provide a steady and uninterrupted flow.

Another object of the invention resides in providing a nipple for attachment to a container neck, said nipple having a tubular nozzle secured to it in angular relation thereto, said nozzle being enlarged at its end adjacent said nipple and being formed with an aperture in its enlarged end in proximity to said nipple and at the upper portion of said spout.

With the foregoing and other objects in view, which will appear in the following description, the invention resides in the novel combination and arrangement of parts and in the details of construction hereinafter described and claimed.

In the drawings illustrating my invention:

Fig. 1 is a perspective view of a container showing an embodiment of my invention applied thereto.

Fig. 2 is a sectional view taken on line 2—2 of Fig. 1 and drawn to an enlarged scale.

Fig. 3 is a perspective view of my improved spout detached from the container.

Fig. 4 is a view similar to Fig. 3 of a modified form of my invention.

In the removal of the contents from various containers, such as cans, drums, carboys, and the like, considerable difficulty is encountered where such containers are of substantial proportions due to the periodic influx of air into the container to take the place of the liquid contents removed therefrom. When the contents are poured from such container 45 in the usual manner no steady stream of definite formation or direction of flow is to be had. On the contrary, an irregular discharge usually results, which makes it extremely difficult to direct the contents into 50 the bottle or receptacle to be filled, frequently causing the spilling of the same and the waste thereof. With my invention I provide a simple spout which may be readily inserted into the neck of the container in place of the usual stopper provided therefor, which spout is so shaped as to emit a stream of uniform

formation and is further formed with a vent for supplying air to the container as the contents thereof is removed, thereby insuring a steady and continuous flow from the spout 60 regardless of the degree of inclination of the container while the same is being emptied.

Although it is readily apparent that my invention can be used to drain any type of container having a neck formed thereon, such as cans, drums, carboys, or the like, I have shown in the drawings for the sake of illustration, a cylindrical container A formed with a body portion 10 having applied thereto two heads 11 and 12 by means of seams 13. The head 11 is provided with a filler and drain opening 14 and an outwardly flared neck 15 issuing from said opening and adapted to receive a suitable stopper not illustrated in the drawings. The neck 15 is further provided with a flange 16 by means of which the same may be soldered to the head 11 or otherwise secured thereto in any suitable manner. Such containers being well known in the art are not considered as forming any feature of the invention.

The invention proper consists of a spout B which is formed with a nipple 17 provided with an outwardly extending flange 18. This nipple tapers away from the flange 18 and is of such dimensions that the same may be readily inserted into a standard neck, such as the neck 15, for attachment thereto in place of the usual stopper furnished with the container. To the nipple 17 is attached a nozzle 19 which is tapered in formation and which is enlarged at one end as indicated at 20, for attachment to the nipple 17, said nozzle being formed with a restricted opening 21 at its other end for discharging the liquid therefrom. The enlarged end 20 of nozzle 19 is provided with an annular flange 22 similar to the flange 18 and complementing the same. The nipple 17 and nozzle 19 are secured together through the agency of the flanges 18 and 22 by means of an annular ring or fastening member 23 which is U-shaped in cross section and envelopes both of these flanges and clamps the same securely together. The joint between said nozzle and nipple may be further soldered to insure a tight and rigid construction. The nozzle 19 is so formed that the same issues angularly from the nipple 17 so that when the nipple 17 is arranged with its axis in a horizontal position said nozzle 19 depends therefrom in an outwardly extending direction. When

the nozzle is attached to the drum or container A, as shown in Fig. 1, and the same tilted to a horizontal position, said nozzle 19 becomes so disposed as to readily permit of placing a bottle or other receptacle beneath the same and thereby permit of filling said bottle from the container. By tapering the nozzle 19 a stream of uniform formation and of substantially the same proportions as the opening 21 is secured.

For admitting air to the container to take the place of the liquid contents removed therefrom, I employ a vent which is formed by providing a hole 24 in the nozzle 19 in the uppermost portion thereof in close proximity to the ring or fastening member 23 so that when the spout is situated as shown in Figs. 1 or 2 said opening provides the shortest path between the empty space within the interior of the drum proper and the exterior atmosphere.

In operation the usual stopper is removed from the container and the spout B attached thereto by inserting the nipple 17 into the neck 15 of said container with the nozzle 19 issuing outwardly toward the circumference of the same. Now tilting the container in the direction of the spout B the liquid enters the nipple 17 and nozzle 19 and flows therefrom. As soon as this occurs air enters the vent 24 following along the upper portion of the nipple 17 and along the interior of the head 23 of the container where the same enters the vacant space within said container. As the container is further tilted the flow continues even when the level of the liquid contents within the same stands considerably above the spout B, in which case the stream of air entering the container, when in its partly inclined position, continues to flow due to the partial vacuum created within the container by the discharge of the container contents and to the atmospheric pressure tending to force the air inwardly into said container. In such cases the air bubbles up through the body of the liquid within the container, as indicated in dotted lines at 25 in Fig. 1, allowing the liquid contents to flow from the nozzle in a steady and uniform stream to enable the user to fill bottles or other receptacles with ease and without danger of spilling the liquid removed from the container.

For the purpose of permitting the attachment of my improved spout to containers formed with threaded necks as illustrated in Fig. 4, a spout C of similar construction to spout B and which consists of a nozzle 19 the same as that shown in Fig. 3 is attached to a nipple 26. This nipple has threads 27 rolled or pressed into the same by means of which said nipple may be conveniently screwed upon the conventional type of threaded neck frequently found on cans, drums, or the like.

Excepting for such nipples, the spout C is identical in construction to the spout B having the vent 24 situated in the uppermost portion of the nozzle 19 and functioning in identically the same manner as previously described.

My invention is highly advantageous in that it forms a simple and inexpensive means of conveniently and effectively removing the contents of a container having a filling or discharge neck formed thereon. The entire invention can be constructed at a nominal cost from sheet metal so that a spout may be furnished with every container as desired. The vent for admitting air to the container to take the place of the liquid removed from the container may be added or formed in the nozzle without appreciable added cost. The spout functions in a highly efficient and effective manner causing a steady flow of liquid from the container in a stream of fixed proportions and direction regardless of the angle of inclination of the container and at the same time directs the stream away from the head of the container so that bottles or other receptacles may be conveniently placed beneath the discharge end of the nozzle and be readily filled therefrom.

Changes in the specific form of my invention, as herein disclosed, may be made within the scope of what is claimed without departing from the spirit of my invention.

Having described my invention, what I claim as new and desire to protect by Letters Patent is:

1. A spout for draining a container having a discharge neck, said spout comprising a nipple for attachment to said container neck, an outwardly extending annular flange formed on the outer end of said nipple, a tubular nozzle formed with a flange thereon complementing said first named flange, and an annular ring of U-shaped cross section enveloping said flanges for holding said nozzle attached to said nipple.

2. A spout for draining a container having a discharge neck, said spout comprising a nipple for attachment to said container neck, an outwardly extending annular flange formed on the outer end of said nipple, a tubular nozzle formed with a flange thereon complementing said first named flange, an annular ring of U-shaped cross section, enveloping said flanges for holding said nozzle attached to said neck, and a vent formed in that portion of said nozzle which is uppermost when the container is tilted in pouring position, said vent being adjacent said flanges and ring.

In testimony whereof, I have signed my name to this specification.

CHARLES T. HELLER.
